US0D1101588S

(12) **United States Design Patent** (10) Patent No.: **US D1,101,588 S**
(45) Date of Patent: ** Nov. 11, 2025

(54) **MOVEMENT SENSOR**

(71) Applicant: **AJAX SYSTEMS CYPRUS HOLDINGS LTD**, Nicosia (CY)

(72) Inventor: **Ilshat Garipov**, Haapsalu (EE)

(***) Term: **15 Years**

(21) Appl. No.: **35/521,715**

(22) Filed: **Apr. 17, 2024**

(80) **Hague Agreement Data**

Int. Filing Date: **Apr. 17, 2024**

Int. Reg. No.: **DM/238422**

Int. Reg. Date: **Apr. 17, 2024**

Int. Reg. Pub. Date: **Jul. 19, 2024**

(51) **LOC (15) Cl.** **10-05**

(52) **U.S. Cl.**

USPC **D10/106.6**

Primary Examiner — Samantha Wood

(57) **CLAIM**

The ornamental design for a movement sensor as shown and described.

DESCRIPTION

1. Movement sensor

1.1 : Perspective

1.2 : Perspective

1.3 : Front

1.4 : Back

1.5 : Left

1.6 : Right

The broken line surrounding the dark image represents the boundary of the claimed design and the de-emphasized or half-toned portions represents unclaimed environment and forms no part of the claimed design.

1 Claim, 6 Drawing Sheets
